LELAND H. HILL, OF COLLINGSWOOD, NEW JERSEY, ASSIGNOR, BY MESNE ASSIGNMENTS, TO ALLIS-CHALMERS MANUFACTURING COMPANY, OF MILWAUKEE, WISCONSIN, A CORPORATION OF DELAWARE

TAP-CHANGING SYSTEM AND APPARATUS FOR TRANSFORMERS

Application filed May 7, 1929. Serial No. 361,029.

This invention relates to improvements in tap-changing systems and apparatus for transformers.

One of the objects of the present invention is to provide an improved system and apparatus of the character referred to which is simpler in construction, more rugged and reliable in operation, and which may be more economically manufactured than such systems and apparatus proposed heretofore.

Other objects and advantages will hereinafter appear.

For the purpose of illustrating the invention, several embodiments thereof are shown in the drawings, wherein

Figure 1 is a schematic showing of a tap-changing system and apparatus for transformers embodying the present improvements, certain of the parts being removed for the sake of clearness;

Fig. 2 is a schematic showing of the improved tap-changing apparatus illustrating the manner of operation thereof, certain of the parts being removed for the sake of clearness;

Fig. 3 is an elevational sectional view of the improved tap-changing apparatus in Fig. 1;

Fig. 4 is a sectional view, the section being taken on the line 4-4 in Fig. 3;

Fig. 5 is an enlarged fragmentary plan view of the improved tap-changing apparatus;

Fig. 6 is a sectional view of the improved tap-changing apparatus, the section being taken on the line 6-6 in Fig. 5;

Fig. 7 is a detail sectional view, the section being taken on the line 7-7 in Fig. 5;

Fig. 8 is a view similar to Fig. 7, illustrating a modification;

Fig. 9 is a plan view of Fig. 8;

Fig. 10 is an elevational view, looking toward the left in Fig. 8;

Figs. 11, 12 and 13 are views similar to Fig. 1, illustrating various modifications;

Fig. 14 is a view similar to Fig. 4, showing details of the control mechanism in the system shown in Fig. 12; and

Fig. 15 is a view similar to Fig. 4, showing

details of the control mechanism in the system shown in Fig. 13.

Referring now to Fig. 1, the transformer 10 includes the primary winding 11 connected across the alternating-current supply lines 12 and 13, and the secondary winding 14 having the voltage taps 15, 16, 17, 18 and 19.

The tap-changing apparatus for the switch, designated generally by the reference numeral 20, comprises the switch contact 21 connected to supply line 13 and the switch contacts 22, 23, 24, 25 and 26 connected, respectively, to voltage taps 15, 16, 17, 18 and 19; and the operating member comprising the switch elements 27 and 28 fixed on shaft 29 for rotary movement together and electrically connected to suitable rings 30 and 31 which are engaged by suitable brushes 32 and 33 providing connection between the switch elements and the ends 34 and 35 of an auto-transformer 70 winding 36 having the mid-tap 37.

A switch device 38 is associated with switch mechanism 20 and provided with the contacts 39 and 40 connected, respectively, with the ends 41 and 42 of secondary winding 14, 75 the switch device having electrical connection with switch contact 21 and being supported for pivotal movement upon the pin 43.

Rotary movement is imparted to shaft 29 by the rack 44 and associated pinion 45 fixed on the shaft. Excitation of winding 46 provides for right-hand movement of rack 44 to effect counter-clockwise rotation of switch member 27-28, while excitation of winding 47 provides for left-hand movement of the 85 rack to effect clockwise rotation of the switch member.

The load is connected across lines 12 and 48, the latter being connected, as shown, to midpoint 37 of the auto-transformer.

The operation of the system thus far described will now be explained. In Fig. 1, the switch member 27-28 is shown in one of its extreme positions to provide for full or maximum boosting action of transformer 10 with respect to the load line 12-48, at which time switch device 38 will be in engagement with contact 40 to establish an operating connection between switch mechanism 20 and the end 42 of winding 14. In this position of

member 27—28, the switch elements comprising the same are bridged by contact 22 to short-circuit winding 36 so that the voltage at mid-tap 37 will be equal to that at tap 15.

- 5 If the load diminishes, the load voltage is decreased correspondingly by excitation of winding 46, in the manner hereinafter explained, to effect counter-clockwise rotation of member 27—28 through such angular distance as is necessary to bring the load voltage back to normal value.

With member 27—28 bridging the switch contacts 22 and 23, as shown in Fig. 2, winding 36 will be connected across taps 15 and 16, so that the voltage at mid-tap 37 will be equal to a value intermediate the voltage values at taps 15 and 16.

In the position of switch member 27—28 in which the switch elements are both in contacting engagement with contact 23, and winding 36 accordingly short-circuited thereby, the voltage at mid-tap 37 will be equal to that at tap 16.

When switch elements 27 and 28 are moved into position to bridge the contacts 23 and 24, the voltage of load line 12—48 will be still further decreased, at which time the voltage at mid-tap 37 will be equal to a value intermediate the voltage values at taps 16 and 17.

30 In like manner, continued counter-clockwise movement of switch member 27—28 will provide for still further decrease in the voltage at mid-tap 37 in steps, the next lower voltage being that at tap 17 in which switch elements 27 and 28 are bridged by switch contact 24; the next lower voltage being intermediate the voltages at taps 17 and 18, at which time the switch elements will be in position to bridge the contacts 24 and 25; the next lower voltage being that at tap 18, at which time switch elements 27 and 28 will be bridged by switch contact 25; the next lower voltage being intermediate the voltages at taps 18 and 19, at which time switch elements

45 27 and 28 will bridge the contacts 25 and 26; the next lower voltage being that at tap 19, at which time switch elements 27 and 28 will be bridged by switch contact 26; the next lower voltage being intermediate the volt-

50 ages at tap 19 and the winding end 42, at which time switch elements 27 and 28 will bridge the contacts 21 and 26. When the switch member is moved into position in

55 which the switch elements 27 and 28 are bridged by contact 21, winding 36 will be short-circuited through this contact. The load voltage across lines 12 and 48 will then be equal to the supply voltage across lines 12 and 13.

60 During further counter-clockwise rotation of the switch member, a suitable lug or projection 49 carried by switch element 27 enters between the spaced legs 50 and 51 forming part of switch element 38, and by engagement with leg 50, as more clearly shown in

Fig. 5, causes clockwise movement of switch 38 into contacting engagement with contact 39, at which time both switch elements 27 and 28 will be in contact with and bridged by switch contact 21.

70 Further counter-clockwise movement of member 27—28 will provide for still further reduction in the load voltage on account of the reversal of switch 38 to establish an operating connection between the switch mechanism 20 and the other end 41 of winding 14. Transformer 10 will now have a bucking action with respect to the supply voltage. When switch elements 27 and 28 bridge the contacts 22 and 21, winding 36 80 will be connected across end 41 and tap 15 of winding 14. The voltage at mid-tap 37 will then be intermediate the voltages at end 41 and tap 15.

85 Upon further movement of switch elements 27 and 28 to the position in which the same are bridged by contact 21, winding 36 will be short-circuited by this contact so that the voltage at mid-tap 37 will be equal to that at tap 15.

90 The next lower voltage will be provided when switch elements 27 and 28 are in position to bridge the contacts 23 and 22, at which time the voltage at mid-tap 37 will be intermediate the voltages at taps 15 and 16. 95

95 In like manner, it will be understood that continued counter-clockwise movement of operating member 27—28 will provide for still further decrease in the voltage at mid-tap 37, the respective succeeding values being equal to the voltage at tap 16, next to a voltage intermediate the voltages at taps 16 and 17, next at a voltage equal to that at tap 17, next at a voltage intermediate the voltages at taps 17 and 18, next at a voltage 105 equal to that at tap 18, next at a voltage intermediate the voltages at taps 18 and 19, and finally at the minimum voltage equal to the voltage at tap 19 when switch elements 27 and 28 are both in contacting engagement 110 with contact 26 and are bridged thereby, the switch member 27—28 then being in its other extreme position in which full bucking action of winding 14 is obtained.

115 During the first revolution of switch member 27—28 in a clockwise direction, the load voltage will be increased in steps from the minimum voltage value to the value at the intermediate or neutral point in the voltage range in which switch elements 27 and 28 120 will be in contacting engagement with contact 21 and bridged thereby. Upon movement of the switch member through the second clockwise revolution, the projection 49 carried by switch element 27 will first enter between legs 50 and 51 of switch 38 and, by engagement with leg 51, will effect counter-clockwise rotation of switch 38 into contacting engagement with contact 40. During this second revolution of switch member 125

27-28, therefore, the switch mechanism 20 will be connected to the end 42 of transformer winding 14, and the voltage increased in steps from the intermediate or neutral value in the voltage range to the maximum voltage value in which switch elements 27 and 28 are in their extreme position as shown in Fig. 1, and are bridged by contact 22.

10 From the foregoing it will be seen that in the present improved tap-changing apparatus, the switch elements 27 and 28 constitute means providing for concurrent connection of both ends 34 and 35 of winding 36 with the individual taps of winding 14 or connection of one of the ends of winding 36 with one of the taps concurrently with connection of the other end of winding 36 with another of the taps. In other words, switch member 27-28, in the present embodiment of the invention, provides for conditions in which winding 36 is either short-circuited by the individual taps of winding 14 or is connected across adjacent taps. It will further be seen that switch device 38 and associated parts constitute means operable to establish operating connections between switch mechanism 20 and either of the end points 41 and 42 of winding 14, the transformer winding 14 having a boosting action in the system when switch 38 is in contacting engagement with contact 40 and having a bucking action in the system when switch 38 is in contacting engagement with contact 39.

35 By reason of this construction and connection, the same portion of winding 14 is effective during different parts of the entire voltage range provided by switch mechanism 20. That is, during the first complete revolution of switch member 27-28 in a counter-clockwise direction, winding 14 will be effective to provide for regulation of the voltage in steps from the maximum value, in which switch elements 27 and 28 are in their initial position and bridged by contact 22, to the intermediate or neutral value in the voltage range in which the switch elements are both in contact with and bridged by contact 21, at which time the load voltage will be equal to the supply voltage, as explained. During the next revolution of operating member 27-28 in a counter-clockwise direction, prior to which switch 38 is reversed, as explained above, the same portion of winding 14 which was effective before will be effective again to provide for voltage regulation throughout the lower half of the voltage range and in steps from the intermediate or neutral value to the minimum value which is equal to the voltage value at tap 19.

60 The present construction, it will be seen further, provides for a considerably greater number of operating positions or voltage steps and there are taps to transformer winding 14. Furthermore, at operating posi-

tions in which switch elements 27 and 28 are bridged by adjacent contacts of switch mechanism 20, the current will be equally divided between elements 27 and 28 and the associated connections to ends 34 and 35 of winding 36, so that the switch contacts then operating will have to carry only one-half of the main load current.

75 Figs. 3 to 7 show in a general way a proposed construction of the system and apparatus shown in Fig. 1. As shown in Fig. 3, it is proposed to mount or support the various parts comprising the present improved system in a single casing 52 having the lower chamber 53 containing the main transformer 14 and auto-transformer 36, the intermediate chamber 54 containing switch mechanism 20, and the upper chamber 55 containing the actuating and control mechanism for the switch mechanism. The lower chamber contains oil to about the level indicated by line 56 to completely submerge the transformer apparatus, while the intermediate chamber 54, which is entirely independent of the bottom and top chambers 53 and 55 and is sealed therefrom, contains oil to about the level indicated by line 57, so that switch mechanism 20 is entirely submerged and operates at all times in oil. The main transformer leads may be taken out through casing 52 by way of suitable bushings 58, as indicated.

80 The switch 38 may be comprised of the resilient strips or arms 59 and 60 spaced by and secured to the switch part 61 by rivets 62, these strips or arms carrying at their outer ends complementary contact shoes 63 and 64, shaped as indicated, and urged toward each other by the spring action of the arms into firm contacting engagement with contacts 39 and 40.

85 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

90 100 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

105 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

110 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

115 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

120 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

125 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

130 The switch elements 27 and 28 are constructed, in a similar manner, of resilient strips or arms secured in any suitable manner to an insulating block or disc 65. For example, in Fig. 7, switch element 28 is indicated as being comprised of the spring strips or arms 66 and 67 carrying at their outer ends the complementary contact shoes 68 and 69.

- with main contacts 21 and 22, extend slightly beyond the edges of the latter so that the arcing shoe 72 engages and disengages the associated contacts before engagement or disengagement of contact shoes 68 and 69 with contacts 21 to 26 during rotary operating movement of switch member 27—28 in either direction.
- An auxiliary or arcing switch element, 10 similar to element 28', is disposed above and electrically connected to the main switch element 27 and, like switch element 28', is secured to the block or disc 71 and disposed for engagement with the auxiliary arcing contacts.

The switch mechanism 20 is mounted on the insulating base 73 forming a partition between chambers 53 and 54, and which is provided with the upwardly extending annular flange 74 through which terminal posts 75 lead to the respective switch contacts 21 to 26 and the associated arcing contacts. The terminal post 76 leads to switch contact 39, while the terminal post 77 leads to brush 33. A similar post (not shown) provides a connection to brush 32. The tubular member 78 is provided with the outwardly extending flange 79 and has a press fit on the bearing post 80 having its lower end portion 30 extending loosely through the center of base 73 for rotary movement therein. The nut 81 threaded on the lower end of post 80 operates to hold the same in assembled relation and for rotary movement with respect to base 73. The rings or discs 30 and 31, insulating discs 71 and 65, and a spacing block 82, are clamped firmly between flange 79 and the nut 83 threaded on the upper end of tubular member 78, as shown.

40 Shaft 29 may be coupled to the upper end of tubular member 78 by a pin 84.

In the modification shown in Figs. 8, 9 and 10, a plurality of arcing contact shoes 85 to 89 are substituted for the single arcing shoe 72 in Fig. 7, these contacts being secured to the uprightly disposed insulating block 90 secured in any suitable manner to the upper insulating disc 71. Contact shoes 91 to 95, 45 complementary, respectively, to contact shoes 85 to 89, are supported by spring clips or arms 96 secured to the uprightly disposed insulating post 97 secured to the outer portion 98 of the switch contact 99, the latter being engaged by the main contact shoes 100 which correspond to the contact shoes 68 and 69 in Fig. 7. A metal insert 101 provides connection with contact shoe 85. Contact shoes 86 and 87 are electrically connected by a metal 50 insert 102, while contact shoes 88 and 89 are electrically connected by a metal insert 103. Contact shoes 91 and 92 are electrically connected by a metal insert 104 and contact shoes 93 and 94 are electrically connected by a metal 55 insert 105, contact shoe 95 being electrically

connected with the outer part 98 of contact 99 by a metal insert 106.

The construction and arrangement just described provides for series connection of the auxiliary or arcing contacts with the associated main contacts 100, the current passing through contact shoes 85 and 91, then through insert 104 and contact shoes 92 and 86, through insert 102 and contact shoes 87 and 93, through insert 105 and contact shoes 94 and 88, through insert 103 and contact shoes 89 and 95, and through insert 106 to contact 99. The arc is, therefore, broken up into a series of smaller arcs and the arcing action at the individual arcing contact shoes decreased accordingly.

The automatic control means, whereby switch mechanism 20 is operated automatically in one direction or the other to maintain the load voltage across lines 12 and 48 substantially constant, will now be described. The relays 107 and 108 are provided, respectively, with windings 109 and 110 connected, as shown, to the voltage transformer 111 having its primary 112 connected across lines 12 and 48 at a point in proximity to the tap-changing apparatus, and to the line-drop compensator of well-known construction and which is indicated generally by reference numeral 113. The arrangement is such that at load conditions during which the load voltage is substantially normal, excitation of relay winding 109 will be such as to hold the associated switch element 114 out of bridging relation with contacts 115, while the excitation of relay winding 110 will be insufficient to effect movement of the associated switch element 116 into bridging relation with contacts 117.

Upon decrease in the load voltage below normal, excitation of relay winding 109 will be decreased by such amount as to permit of movement of switch element 114 into bridging relation with contacts 115 under the action of gravity or suitable spring means. Upon increase in the load voltage to a value above normal, excitation of relay winding 110 will be increased by such amount as to make this winding effective to cause movement of switch element 116 into bridging relation with contacts 117.

Upon the bridging of contacts 117 by switch element 116, the winding 118 of relay 119 will be connected to the supply source 120 through winding 46, switch 121 and connection 122. Winding 46 will, therefore, be excited and accordingly become effective to impart right-hand movement to rack 44. Upon such movement of the rack, the shank 123 of the switch 124 will ride up and down the teeth of the rack to effect opening and closing operation of switch 124, the arrangement being such that when the end of shank 123 is in position between adjacent teeth switch member 27—28 is in one of its operat-

- ing positions, while, on the other hand, in other positions of the rack in which shank 123 does not rest exactly between adjacent teeth, the cam action of the latter with respect to the shank will hold the associated switch 124 in bridging relation with respect to contacts 125, 126 and 127. The contacts 125, 126 and 127 may be made in the form of yieldable spring clips to allow for reciprocatory movement of switch 124 while the same is in bridging or contacting relation with the contacts, the switch being urged at all times out of bridging relation with respect to the contacts and into seating engagement with rack 44 by the spring 128. Upon excitation of relay winding 118 and closure of switch 124 upon occurring right-hand movement of rack 44, the associated switch element 129 is moved into bridging relation with contacts 130 to complete a circuit between winding 46 and supply 120, independently of contacts 117, such circuit being made through connection 131, contacts 125 and 126, connection 132, contacts 130, relay winding 118, winding 46, switch 121 and connection 122. In event the resulting right-hand movement of rack 44 and the accompanying counter-clockwise rotation of switch member 27-28 provides for decrease in the load voltage to normal at a time when the switch member is in a position intermediate one of its operating positions, and switch element 116 is permitted to move out of bridging relation with contacts 117, an exciting circuit for winding 46 will be maintained through the contacts 130 and contacts 125 and 126 until the switch member moves by such further amount as to place the same in the next operating position thereof, at which time the switch shank 123 will be pressed into position between the adjacent rack teeth and switch element 124 moved out of bridging relation with the contacts 125 and 126 to open the exciting circuit for winding 46.
- When switch member 27-28 reaches its extreme position in which the switch elements comprising the same are bridged by contact 26 to provide for full bucking action of winding 14, the switch 121 will be opened through the instrumentality of the lever 133 pivotally mounted at 134 and disposed for engagement by the lug 135 carried by rack 44.
- Upon the bridging of contacts 115 by switch element 114, a circuit will be completed between winding 47 and supply 120 through contacts 115, winding 136 of relay 137, switch 138 which will have closed during previous right-hand movement of rack 44, winding 47 and connection 122. Upon excitation of relay winding 136, the switch element 139 associated therewith will be moved into bridging relation with contacts 140 to establish another operating circuit between winding 47 and supply 120 through connection 131, contacts 125 and 127, connection 141, contacts 140, relay winding 136, switch 138, winding 47 and connection 122, the closed contacts 140 accordingly providing for an operating circuit between winding 47 and supply 120 independently of contacts 115 and the associated switch element 114.
- In event, therefore, the occurring left-hand movement of rack 44, accompanied by clockwise rotation of switch member 27-28 results in increase of the load voltage to normal at a point in the operating movement of the switch member at which the same is intermediate one of the operating positions thereof, in which case excitation of relay winding 109 will be such as to effect movement of switch element 114 out of bridging relation with contacts 115, the exciting circuit between winding 47 and supply 120 will be maintained by the closed contacts 140 and contacts 125 and 127, as explained, until the rack has continued its left-hand movement by such amount as to bring shank 123 of switch 124 in full registration with adjacent teeth of the rack, at which time switch 124 will be moved out of bridging relation with contacts 125 and 127 under the action of spring 128 to open the exciting circuit of winding 47. Upon movement of switch member 27-28 to its extreme position, as shown in Fig. 1, in which the switch elements comprising the same are in contact with and are bridged by contact 22 to provide for full boosting action of transformer winding 14, lever 133 will be engaged by the lug 142 carried by rack 44 and moved into the position shown to open switch 138.
- From the foregoing, it will be seen that automatic means have been provided for effecting operating movement of switch member 27-28 in a clockwise direction upon decrease in the load voltage below normal, and in a counter-clockwise direction upon increase in the load voltage above normal, the operating movement of the switch member being continued until the load voltage is restored substantially to normal, the switch 124 and associated parts providing for operation of the switch member in such wise that the same always comes to rest in one of its operating positions in which switch elements 27 and 28 either bridge adjacent switch contacts or are bridged by one of the individual contacts.
- When the present improver tap-changing system and apparatus is used in a high-tension system, it is proposed to connect the same in the manner shown in Fig. 11. In this figure, the various connections and parts are designated by the same reference numerals designating similar and corresponding parts in Fig. 1. In Fig. 11, the arrangement and manner of operation is the same

as in Fig. 1, except that the switch mechanism 20 is connected to the high tension line 13 through the current transformer 143 connected, as shown, to switch contact 21 and 5 the mid-tap 37 of the auto-transformer winding 36. By this arrangement the switch mechanism 20 is protected from direct connection with the high-tension line, the influence of transformer winding 14 in 10 having a boosting or bucking action with respect to the supply voltage being made through current transformer 143.

In Figs. 12 and 14, a proposed construction and arrangement is shown whereby the relays 15 119 and 137 in Fig. 1 may be omitted, the various connections and parts being given the same reference numerals as similar and corresponding connections and parts in Fig. 1.

Upon movement of switch element 116, in 20 Fig. 12, into bridging relation with contacts 117, an exciting circuit between winding 46 and supply 120 will be established through contacts 117, connection 144, connection 145, winding 46, switch 121 and connection 122.

25 Upon the occurrence of right-hand movement of rack 44, the switch element 146, which is pivotally mounted at 147 and provided with the projection 148 disposed in the path of movement of the rack teeth, will be tilted in 30 a counter-clockwise direction into contacting engagement with contact 149 as the projection 148 rides over each tooth of the rack. Upon engagement of switch element 146 with contact 149, an exciting circuit between winding 46 and supply 120 is established independently of contacts 117, such circuit being completed through connection 150, switch element 146 and contact 149, connection 145, winding 46, switch 121 and connection 122.

40 In event the load voltage is brought back to normal when the switch member 27-28, in Fig. 1, is at a point in its operating movement intermediate adjacent operating positions of the switch member, the engaging 45 switch element 146 and contact 149 will maintain excitation of winding 46 although switch element 116 will have moved out of bridging relation with the associated contacts 117. The arrangement is such that when the switch

50 member 27-28, in Fig. 1, has moved by such further amount as to bring the same to the next operating position, rack 44 will be in such position that adjacent teeth in the rack receive projection 148 to permit return movement of switch element 146 to its central position under the action of suitable springs 151 whereupon the same is in position out of 55 contacting engagement with both the associated contacts 149 and 152. The action in

60 the opposite direction is the same, that is, upon decrease in the load voltage below normal switch element 114 will move into bridging relation with contacts 115 to complete the circuit between winding 47 and supply 65 120 through contacts 115, connection 153,

switch 138 which will have previously closed consequent to previous right-hand movement of rack 44, winding 47 and connection 122. Upon the occurrence of left-hand movement of rack 44, the engaging action of the rack teeth with projection 148 of switch element 146 will cause clockwise pivotal movement of the same into contacting engagement with contact 152, thereby establishing an operating circuit between winding 47 and supply 120 independently of switch 114 and contacts 115, such independent circuit being made through connection 150, switch element 146 and contact 152, connection 153, switch 138, winding 47 and connection 122. During left-hand movement of rack 44, and during times when the switch member 27-28, in Fig. 1, is in any position intermediate any of its operating positions, the rack teeth will cause 70 engagement of switch element 146 with contact 152. When, however, switch member 27-28 is in any of its operating positions, the adjacent teeth then coacting with projection 148 of switch element 146 will be in position to receive the same and permit movement thereof to central position under the action of springs 151.

75 From the foregoing it will be seen that, in the arrangement in Figs. 12 and 14, the action is the same as in Fig. 1, the switch element 146 and associated parts providing that switch member 27-28 always come to rest in one of its operating positions in which the switch elements 27 and 28 comprising the same are either bridged by one of the individual contacts 21 to 26 or bridge adjacent contacts.

80 In Figs. 13 and 15, proposed connections and arrangements are shown having the same operating action as the connection and arrangement shown in Fig. 1, but wherein an electric motor is employed in lieu of the rack-and-pinion mechanism 44-45 and solenoids or windings 46 and 47. In the modification in Figs. 13 and 15, an electric motor 154 is connected to the drive shaft 155 having a worm 156 meshing with worm wheel 157 fixed on shaft 158, the latter corresponding to shaft 29 in Fig. 1. Fixed on drive shaft 155 is the brake drum 159 with which are associated the brake shoes 160 carried by levers 161 pivotally mounted at 162. The tension spring 163 is connected to levers 161 as shown, and operates to urge shoes 160 into braking engagement with drum 159. Armatures 164 associated with levers 161 are urged toward each other upon excitation of winding 165 to release shoes 160 from braking engagement with drum 159 against the action of spring 163. Upon increase in the load voltage above 90 normal, excitation of relay winding 166 will be increased by such amount as to effect movement of switch elements 167 and 168 into bridging relation with the respective associated contacts 169 and 170, thereby completing an operating circuit between motor 154 95 and supply 120.

and supply 171 through connection 172, contacts 170, connection 173, the motor field winding 174, switch 175, connection 176, relay winding 177, connection 178, contacts 169, 5 connection 179, connection 180, brake-releasing winding 165 and connection 181. The motor 154 now operates to impart rotary movement to shaft 158 in a counter-clockwise direction. When the switch member 27-28, 10 in Fig. 1, reaches its full boosting position in which the switch elements 27 and 28 are bridged by contact 22, the lug 182 fixed on shaft 158 will engage leg 183 with which the switch-actuating element 185 is provided and 15 impart counter-clockwise movement to the latter into engagement with switch 175 to open the same. During periods in the rotary movement of shaft 158 when the switch member 27-28, in Fig. 1, is in a position intermediate any 20 of its adjacent operating positions, the teeth of the gear 186 fixed on shaft 158 will operate to effect engagement of the switch member 187 with the associated contacts 188, 189 and 190, the action being the 25 same as that between the teeth of rack 44 and switch member 123, in Fig. 1. An operating circuit between motor 154 and supply 171 is thereby established independently of the closed contacts 169 and 170, such independent 30 circuit being made through connection 181, brake-releasing winding 165, connection 180, contacts 190 and 188, connection 191, closed contacts 192, relay winding 177, connection 176, switch 175, motor field winding 174, connection 173, closed contacts 193 and connection 172. In event, therefore, the load voltage be decreased to normal and contacts 169 and 170 accordingly opened before switch 35 member 27-28, in Fig. 1, reaches one of its 40 operating positions, an exciting circuit for motor 154 and brake-releasing winding 165 will be maintained through contacts 188 and 190 and contacts 192 and 193 until the switch member has reached the next operating position, 45 at which time switch member 187 will be received between adjacent teeth of gear 186 to permit of opening movement thereof under the action of spring 194.

Upon decrease in the load voltage below 50 normal, excitation of relay winding 195 will be decreased by such amount as to permit of movement of switch elements 196 and 197 into bridging relation with the respective associated contacts 198 and 199, thereby establishing an operating connection between motor 154 and supply 171 through contacts 199, connection 200, relay winding 201, connection 202, switch 203, field winding 174, connection 210, contacts 198, connection 60 172, motor 154, supply 171, brake-releasing winding 165, connection 180, connection 179 and connection 204. Reverse rotation of the motor will now take place to effect counter-clockwise rotation of shaft 158 and accompanying counter-clockwise rotation of

switch member 27-28 in Fig. 1. Upon excitation at this time of relay winding 201, switch elements 205 and 206 will be moved into bridging relation with the respective associated contacts 207 and 208. An exciting 70 circuit between motor 154 and supply 171 will therefore, be established independently of the closed contacts 198 and 199, such independent circuit being made through connection 181, brake-releasing winding 165, connection 180, contacts 190 and 189, connection 209, contacts 208, relay winding 201, connection 202, switch 203, field winding 174, contacts 207, motor 154 and supply 171. It will be seen, therefore, that in event of the occurrence of counter-clockwise rotation, shaft 158 operates to effect increase in the load voltage to normal at a point in the operating movement of switch member 27-28, in Fig. 1, when the same is in position intermediate any 80 adjacent operating positions, and excitation of relay winding 195 is accordingly increased by such amount as to effect movement of switch elements 196 and 197 out of bridging relation with the respective associated contacts 198 and 199, the exciting circuit for the motor and brake-releasing winding is maintained by switch elements 205, 206 and 187 until switch member 27-28 has reached the 85 next operating position.

During the first counter-clockwise revolution of shaft 158, the lug or projection 182 is received between legs 183 and 184 of switch-actuating element 185, and the leg 183 engaged by lug 182 to cause pivotal movement of this element in a clockwise direction to the position shown when leg 184 is in position in the path of movement of lug 182. At the completion of the second revolution of shaft 155 in a counter-clockwise direction, therefore, lug 182 will engage leg 184 to effect further clockwise pivotal movement of element 185 into engagement with switch 203 to open the same. Similarly, during the first clockwise revolution of shaft 155, lug 182 is received between legs 183 and 184, and leg 184 engaged by lug 182 to cause pivotal movement of element 185 in a counter-clockwise direction to the position shown when leg 183 is in position in the path of movement of lug 182.

While several embodiments of the present invention have been illustrated and described, it will be appreciated that various other modifications or changes may be made without departing from the spirit of the invention or the scope of the claims.

The invention claimed is:

1. In a system of the character described, a transformer winding, switch means operable to render said winding effective to provide for voltage regulation in said system throughout a predetermined voltage range, and second switch means controllable by said first-named switch means during operating 125 130

movement of the latter, said second switch means being operable under control by said first-named switch means to establish operating connections between the same and different points in said winding.

2. In a system of the character described, a transformer winding having voltage taps, and switch mechanism connected to said taps and having an operating member supported for rotary operating movement in a given direction through more than a complete revolution and being operable to provide for voltage regulation in said system throughout a predetermined voltage range upon such movement of said member and in steps from the voltage value at one end of said voltage range where said member is substantially at its initial operating position to the voltage value at the other end of said voltage range where said member is substantially at its final operating position.

3. In a system of the character described, a transformer winding having voltage taps, a second transformer winding; and switch mechanism comprising switch elements supported for rotary movement together and connected respectively to the ends of said second winding, and switch contacts connected respectively to said taps and arranged about the axis of rotation of said elements for engagement thereby, said contacts being operable individually to bridge said elements upon movement of the same to certain operating positions, adjacent contacts in said arrangement being operable conjointly to bridge said elements upon movement of the same to certain operating positions intermediate said first-named positions.

4. In a system of the character described, a transformer winding having voltage taps, switch mechanism comprising contacts connected respectively to said taps and an operating member movable into contacting engagement selectively with said contacts and having predetermined operating positions for such purpose, means including rack-and-pinion mechanism for imparting operating movement to said member, control means for said first-named means, and means operable independently of said control means to effect operating action of said rack-and-pinion mechanism during operating periods of said switch mechanism whereat said operating member thereof is in positions intermediate said predetermined operating positions.

5. In a system of the character described, a transformer winding having voltage taps, switch mechanism connected to said taps and having an operating member supported for rotary operating movement in a given direction through more than a complete revolution and being operable to provide for voltage regulation in said system throughout a predetermined voltage range upon such movement of said member, and a switch de-

vice associated with said switch mechanism and operable to establish an operating connection between the same and either end of said winding, and means carried by said member and disposed for engagement with said switch device to actuate the same at a predetermined point in the operating movement of said member.

6. In a system of the character described, transformer apparatus operable to influence voltage conditions in said system and including a secondary winding having voltage taps, a second transformer winding, means providing for voltage regulation in said system and operable for such purpose to provide for concurrent connection of both ends of said second winding with certain of the individual taps or connection of one of such ends with certain of said taps concurrently with connection of the other of such ends with another of said taps, and means responsive to abnormal conditions in said system and operable upon occurrence of such conditions to effect operation of said first-named means in such wise as to restore such conditions to normal.

7. In a system of the character described, transformer apparatus operable to influence voltage conditions in said system and including a secondary winding having voltage taps, a second transformer winding, means providing for voltage regulation in said system and including a switch member for such purpose supported for operating movement in opposite directions and having various operating positions and being operable when in such positions to provide for concurrent connection of both ends of said second winding with certain of the individual taps or connection of one of such ends with certain of said taps concurrently with connection of the other of such ends with another of said taps, and means responsive to abnormal conditions in said system and operable upon occurrence of such conditions to effect operating movement of said member in such direction as to effect restoration of normal operating condition in said system.

8. In a system of the character described, transformer apparatus operable to influence voltage conditions in said system and including a secondary winding having voltage taps, a second transformer winding, means providing for voltage regulation in said system and including a switch member for such purpose supported for operating movement in opposite directions and having various operating positions and being operable when in such positions to provide for concurrent connection of both ends of said second winding with certain of the individual taps or connection of one of such ends with certain of said taps concurrently with connection of the other of such ends with another of said taps, means responsive to abnormal conditions in said system and operable upon occurrence of

such conditions to effect operating move-
ment of said member in such direction as to
effect restoration of normal operating con-
dition in said system, means operable inde-
pendently of said second-named means to
effect such movement of said member, and
means operable to render said third-named
means effective when said switch member is
intermediate said operating positions and to
render said third-named means non-effective
when said switch member is substantially in
said operating positions thereof.

In witness whereof I hereto affix my sig-
nature this 19th day of April, A. D. 1929.
